UNITED STATES PATENT OFFICE.

JOSEPH ECKERT, OF DAYTON, OHIO.

BOTTLE-CAP REMOVER.

1,328,827.

Specification of Letters Patent. Patented Jan. 27, 1920.

Application filed September 23, 1919. Serial No. 325,677.

To all whom it may concern:

Be it known that I, JOSEPH ECKERT, a citizen of the United States, and resident of Dayton, in the county of Montgomery and State of Ohio, have invented a certain new and useful Improvement in Bottle-Cap Removers, of which the following is a description, reference being had to the accompanying drawings, which form a part of my specification.

My invention relates to an improvement in bottle cap removers, and more particularly to that class which may be adapted either to be screwed to a support or held in the hand of the operator.

The object of the invention is to produce a device for removing caps from bottles which can be attached to a wall or other suitable support, which is simple and inexpensive to manufacture and in the use of which breakage of bottles, in the process of opening, is materially lessened.

With these objects in view the invention consists in the novel construction hereinafter fully described in the specification, illustrated in the drawings and more particularly pointed out in the claims.

In the accompanying drawings forming part of the specification, Figure 1 represents a side view of the device secured to a support and shows a bottle with cap thereon, the cap and the removing device being shown, in solid lines, in engagement preparatory to removing the cap, a portion of the bottle being shown in dotted lines indicating the relative position of the bottle when the cap is released; Fig. 2 is a front view of the device attached to a support; Fig. 3 a top view, and Fig. 4 a view from the under side thereof. Fig. 5 represents a portion of the end of the bottle with the cap removed; Fig. 6 a perspective broken view of the cap, and Fig. 7 a modification in which the fulcrum member is formed on the base member. Like reference numerals indicate corresponding parts throughout the drawings.

In the said drawings, 1 represents a bottle of the type usually employed for bottling mineral waters, etc., the open end of which is capped with a metallic cork lined cap 2, such as is commonly used for bottling purposes, and which has a downwardly turned fluted flange 3 adapted to be pressed over a bead 4, at the open end of the bottle

to retain the liquid therein; 5 represents a base member adapted to be secured to a support 6, which may consist of a wall, post or other fixture suitable for the purpose, or the base member may be of suitable form to be held in the hand of the operator, an overhanging arm 7 projects from the face side of the base member and is provided at its free end with a pair of circularly disposed inwardly inclined depending lip members 8-8' having their lower edges beveled for a purpose which will presently appear. The base member 5 is provided with notches 9 to receive screws 10-10', by which the device may be secured to a support. The edge of the flange 3 extends slightly below the bead 4 of the bottle and to remove the cap it is inserted in the device as shown in Fig. 1, the lip members, 8-8', engaging the free edge of the flanges 3, on the inside thereof, with the face of the cap 2 resting against the head of the screw 10', which serves as, what may be termed, a fulcrum member, and, when in this position pressure on the bottom end of the bottle will cause the face of the cap 3 to spring inward and the beveled edges of the lip members will simultaneously be forced between the said flange and the bead 4, whereby the cap will be forced from its grip on the bottle, which may then be emptied of its contents, the lip members being so formed that they exert no pressure against the bottle during the operation, which is very simple and which can be expeditiously performed without danger of breaking or chipping the bottle, thus overcoming serious objection to all other cap removers or bottle openers with which I am familiar.

In Fig. 7 of the drawings I have shown a slight modification of the device as hereinbefore described, wherein the fulcrum member is shown, at 10", as being formed on the base member, instead of utilizing the head of the screw 10' for the performance of the same function.

From the foregoing description of my invention it will be seen that it possesses a maximum degree of efficiency and as it may be made of a single casting its cost is reduced to a minimum.

It also will be obvious that the details of construction of my improved cap remover as above described, may be varied without

departing from the principle and scope thereof, therefore, I do not wish to limit the invention to such exact description.

Having thus fully described my invention,
5 I claim:

1. In a device of the character described, in rigid combination, a base member adapted to be secured to a support and having an arm extending outwardly therefrom; said 10 arm having a pair of inwardly inclined cap engaging members depending from the free end thereof adapted to engage the closure cap of a bottle, and a fulcrum member positioned on said base member adapted to engage the flat surface of said cap at substantially the center thereof and to coöperate with said lip members to remove said cap from said bottle.
- 15

2. A new article of manufacture, comprising in a single structure; a bottle cap remover consisting of a base member having a fulcrum member and an outwardly extending arm provided at its free end with depending inwardly inclined lip members adapted to engage the closure cap of a bottle and to coöperate with said fulcrum member to remove said cap therefrom, said fulcrum member being positioned to engage the flat surface of said cap at substantially the center thereof.

In testimony whereof I hereunto affix my signature this 16th day of September, 1919.

JOSEPH ECKERT.

In presence of—

CLAIR R. ROLAND,
B. F. BURT.
